Primary Examiner — Xavier Marti-Santos*(74) Attorney, Agent, or Firm* — Notaro, Michalos & Zaccaria P.C.(57) **CLAIM**

The ornamental design for a vacuum shaver as shown and described.

DESCRIPTION

FIG. 1 is a top, left, front perspective view of a vacuum shaver showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines in the figures illustrate portions of the vacuum shaver which form no part of the claimed design.
